ATTORNEY

UNITED STATES PATENT OFFICE.

BENJAMIN B. HILL, OF PHILADELPHIA, PENNSYLVANIA.

INKING-PAD.

SPECIFICATION forming part of Letters Patent No. 352,323, dated November 9, 1886.

Application filed June 17, 1884. Serial No. 135,148. (No model.)

To all whom it may concern:

Be it known that I, BENJAMIN B. HILL, a citizen of the United States of America, residing at Philadelphia, in the county of Philadelphia and State of Pennsylvania, have invented certain new and useful Improvements in Inking-Pads, of which the following is a specification, reference being had therein to the accompanying drawings.

10 This invention relates to that class of inking-pads in which there is a mass of absorbent material having a thin covering of woven fabric; and the invention consists in the peculiar construction and arrangement of parts, 15 hereinafter more particularly described and claimed.

In the accompanying drawings, Figure 1 shows a perspective view of a pad inclosed in its box; Fig. 2, a vertical longitudinal section 20 of a pad detached. Figs. 3, 4, and 5 show sections of various modifications of the frame.

A represents the box or case, which may be of the shape shown or of any other convenient or desired form, and B is a light frame, 25 which may be of any suitable material; but I prefer to make it of sheet-tin, with a projecting flange, b, at top, as shown in Fig. 2. Within this frame, at C, is a layer of some good absorbent material, preferably of felt, and 30 around the whole is a covering, D, of some thinner fabric—such as a closely-woven cotton cloth with a satin finish—which is secured in place by cementing, sewing, or in any other convenient way.

35 In lieu of the form of frame shown in Fig. 2, the frame may be of plain flat wire, as shown in Fig. 3, or it may be curved in cross-section, as shown in Fig. 4, or have a flange both at top and bottom, as shown in Fig. 5. When 40 made as shown in Fig. 4, the curved-over edges will serve the same purpose to a considerable extent as the flanges shown in Figs. 2 and 5.

By this construction a very compact inking-pad is formed that can be readily and cheaply 45 made, and can never get out of order, and can be readily inked by dropping a few drops of ink over its surface, for any ink dropped on the surface is readily absorbed by the felt and is gradually given off to the stamp applied to 50 the surface of the pad.

It will be observed that the pad as shown in Fig. 2 is complete in itself as an article of manufacture, and that it can be readily put up in the form shown in that figure and supplied to stamp-dealers, who may put them in 55 any suitable box or pad-receptacle to suit their trade or the fancy of their customers.

I prefer the form of frame shown in Fig. 2, because the flange b serves to keep the edges of the felt from rising and working above the 60 top of the frame B.

I am aware that it is not new to use a metallic ring to keep a covering of cloth in position over an inking-pad, and therefore do not claim this, broadly. I regard my pad as 65 essentially different from the device referred to, for that is incomplete without the box, whereas mine is complete with or without the box, and can be set into any case or box that is large enough to contain it, whether it be of 70 the exact size or not.

I am also aware that a pad has been made consisting of a wooden block having a cushion on its top covered with woven material, which block and cushion were forced into an 75 open-bottomed base, so as to hold the covering between the sides of the base and the block, which block and base, being covered with a paper bottom, are not impervious, and I make no claim to this construction, as it has 80 neither my close-bottomed box nor a frame capable of receiving the filling.

I am also aware that a pad consisting of pieces of felt or cloth has been set into a close-bottomed box, and make no claim to such 85 construction.

What I claim as new is—

1. As a new article of manufacture, an inking-pad having a filling, an inclosing frame therefor, and a flexible covering passing over 90 the top of the filling and under both frame and filling and securing the two together, substantially as described.

2. An inking-pad having the following elements: the close-bottomed box A, the interior 95 hollow frame, B, the filling inclosed in said frame, and the flexible covering D, holding the filling within the frame and passing between the frame and the box, whereby said box performs the double function of holding the ink 100

with which the filling is saturated and securing the covering on the frame, substantially as described.

3. In an inking pad, a frame inclosing the filling and having a projection, *b*, to keep said filling from rising above the frame, substantially as described.

In testimony whereof I affix my signature, in presence of two witnesses, this 14th day of June, 1884.

BENJAMIN B. HILL.
